UNITED STATES PATENT OFFICE

2,598,763

GRILLE

William C. De Roo, Holland, Mich., assignor to Hart & Cooley Manufacturing Co., Holland, Mich., a corporation of Michigan

Application May 16, 1949, Serial No. 93,471

2 Claims. (Cl. 98—40)

1 The present invention is directed to an especially simple, economical and effective grille, for use in the passage of air from flues or pipes or the like which carry air for conditioning rooms or other enclosures, to either elevate the temperature of the room during the colder seasons of the year or lower it in the summertime. Such grille is made from a single plate of flat metal, and with it air passing therethrough is passed uniformly and is directed outwardly in diverging streams so that the volume of air passing the grille is generally in the form of a frustum of a cone, rapidly enlarging outwardly away from the grille to thoroughly intermix itself with other air in the room, producing a substantially uniform temperature therein. Exceptional simplicity and economy in manufacture, and attainment of substantial uniformity of outward flow of air through the grille and equal distribution over an increasingly progressive and uniformly enlarging area as the air moves away from the grille are attained by the invention, and are the principal objects and purposes thereof.

An understanding of the invention may be had from the following description, taken in connection with the accompanying drawing, in which,

Fig. 1 is an elevation of the single plate grille of my invention.

Fig. 2 is a section therethrough substantially on the plane of line 2—2 of Fig. 1 with means for connecting the grille with an air flue or stack, and a gasket for sealing the grille against a wall surface being conventionally added thereto and,

Fig. 3 is a fragmentary enlarged perspective view of a portion of the grille.

Like reference characters refer to like parts in the different figures of the drawing.

A flat plate of circular metal is cut and formed by punch press operation to leave a small circular disk 1 at the center of the plate and a flat ring 2 at the peripheral portions thereof, connected by a plurality of radially disposed narrow spokes 3, said disk, ring and spokes remaining in the same plane. The peripheral edge portions of the ring 2 are formed to provide a narrow width continuous flange 4 at the rear side of the grille, within which a sealing gasket 5 of rubber or equivalent material is adapted to be placed, to bear against the wall of a room, for example, in which the grille is installed at the outlet end of an air flue or stack.

The sectors between the radially disposed spokes 3, the outer edge of the central disk 1 and the inner edge of the peripheral ring 2 are formed in a plurality of successive spaced vanes

2 7 in each section which are located in arcs of circles, the common center of which is the center of the grille, or of the ornamental cap, indicated at 6, which may be connected at a central opening in the disk 1, though not essential so far as the invention is concerned. Said vanes extend inwardly and are located generally at an angle substantially of 45° to the plane of the plate from which they are struck. All except the outermost and longest vane 7 in each section have narrow connections at their ends to the spokes 3, the remaining portions of said vanes being severed from the sides of said spokes, as best shown in Fig. 3.

15 It will be noted that the vanes are severed from the sides of the spokes except at the ends so that no flange or lip appears along the edge thereof to impede the flow of air between the vanes. The passages between the vanes are completely unobstructed from one end thereof to the other.

Such vanes are spaced so that lines paralleling each other and at right angles to the plane of the grille plate which touch the free edges of said vanes pass through narrow arc-shaped passages between such inner edges of the vanes and the outer edges of the next adjacent vanes. But other air which at the inner side of the grille is moving in lines perpendicular to the axis of the grille plate strikes against the inner inclined sides of the vanes and is directed outwardly at angles not exceeding substantially 45° to the plane of the grille plate. The width of the passage between adjacent vanes is less than the distance between the vanes at their points of connection with the radial spokes and therefore also less than the length of the passage thereby produced whereby the air passages between adjacent vanes are longer than they are wide. With such construction air is substantially uniformly distributed in a frustoconical body, the cross areas of which, parallel to the face of the grille plate, progressively increase but at the same time there is not left an appreciable central cone outwardly from the center of the grille plate not supplied with the conditioned air as it passes therethrough; but the air passes through the grille, and whether of an increased or decreased temperature with respect to the room temperature, is largely almost uniformly delivered to the other air in the room in like volume at like distances outwardly from the grille.

The radially disposed spokes 3 are quite narrow and it has been found in this construction of elongated unobstructed passages between vanes which are longitudinally arcuate and terminate

at their ends closely adjacent each other that a vacuum ring is produced around the grille which causes the emerging air to be diffused outwardly along the ceiling or wall in which the grille is located. Thus the air blankets the wall or ceiling in a curtaining effect throughout 360° around the grille. This type of air movement is distinguished from that produced by other grilles containing directional vanes where the air is directed outwardly at an angle away from the ceiling or wall in which the grille is located.

For the attachment of the grille to the air carrying flue or stack, or to a register frame which may be disposed between the grille and such flue or stack a ring 8 of sheet metal, having an outwardly extending annular flange 9, is disposed at the inner side of the grille and attached by means of the screws 10 which pass through the ring 2 and connect with flanges 9, said screws, preferably, cutting their own threads in said flanges.

The grille described is substantially the ultimate in simplicity of construction and economy in manufacture. The air is controlled and diffused so as to be widely dissipated into a room to form a curtain of air blanketing the wall or ceiling in which the grille is mounted in which it is entered through the grille.

The invention is defined in the appended claims and is to be considered comprehensive of all forms of structure coming within their scope.

I claim:

1. A grille made from a single piece of sheet metal comprising a circular outer rim and a central disc-like member, a plurality of supporting and dividing arms extending radially outwardly from said disc-like member and connected with said outer rim, thereby dividing the space within said rim into a plurality of sections, a plurality of longitudinally arcuate vanes in each section connected at their ends with the adjacent dividing arms to provide a completely unobstructed passage between adjacent vanes and all vanes in the same section having a common center of curvature, said vanes being posi-

tioned angularly with respect to the plane of said rim and the width of the passage between adjacent vanes being less than the length of said passage, whereby air passing therethrough will be diffused outwardly in all directions to blanket the wall or ceiling in which the grille is mounted with a curtain of air.

2. A sheet metal grille of the character described comprising an outer rim portion having a substantially circular open area within the confines of said rim, a plurality of supporting and dividing arms extending generally radially inwardly from the edge of said open area, means adjacent the center of the open area connecting the inner ends of said arms, whereby said open area will be divided into a plurality of sections, a plurality of longitudinally arcuate vanes in each section connected at their ends with the adjacent dividing arms to provide a completely unobstructed passage between adjacent vanes and all vanes in the same section having a common center of curvature, said vanes being positioned angularly with respect to the plane of said rim and the width of the passage between adjacent vanes being less than the length of said passage, whereby air passing therethrough will be diffused outwardly in all directions to blanket the wall or ceiling in which the grill is mounted with a curtain of air.
